UNITED STATES PATENT OFFICE

ZAN RUCHIN, OF BAY SHORE, NEW YORK, ASSIGNOR TO SAFETY WINDOW DEVICE MFG. CORPORATION, OF BAY SHORE, NEW YORK, A CORPORATION

WINDOW SASH

Application filed April 18, 1930. Serial No. 445,282.

My invention relates to window sashes and refers particularly to window sashes capable of removal from their accompanying window frames.

It is frequently necessary to have access to the outer portion of a window sash, in order to clean the glass, insert a new glass, or to perform other required work thereon.

In the present employed non-removable window sashes, these operations are practically impossible only from the outside of the building with its accompanying danger and inconvenience.

It is evident, therefore, that a removal sash would possess many valuable features.

A sash of this character should be vertically movable within the frame, should be capable of operation with the ordinarily employed frames, should be readily removed and replaced, should be simple of operation, economic of construction and free from possible liability in inoperativeness.

The device of my invention possesses all of the above-mentioned, and other, valuable attributes as will be evident from a consideration of my specification and its accompanying drawings.

In the accompanying drawings, illustrating one form of the device of my invention, similar parts are designated by similar numerals.

Figure 1 is a front view of one form of the device of my invention, the removed position being shown in dot-and-dash lines.

Figure 2 is an enlarged section through the line 2—2 of Figure 1.

Figure 3 is an enlarged section through the line 3—3 of Figure 1.

Figure 4 is an enlarged section through the line 4—4 of Figure 1.

Figure 5 is a perspective view of the fastening member.

Figure 6 is a fragmentary perspective view of a lower portion of the sash.

The particular form of the device of my invention, illustrated in the accompanying drawings, consists of a window sash frame having the sides 10 and 11, the top 12 and the bottom 13, vertically movable within a

window frame having the sides 14 and 15 and the bottom 16.

The outer edge 17 of the side 11 is beveled and has two recesses 18 and 19 for purposes described later. The edge 17 carries a metallic plate 20 which extends across the recess 18. The inner face of the side 11 has two slidable fastening members, or plates, 21 and 22, slidable outwardly through cut-outs in the plate 20.

A detachable fastening member comprises the wooden element 23 having a longitudinal recess 24, and two recesses 25 and 26 corresponding to the fasteners 21 and 22 respectively.

A metallic plate is bent into the part 27, covering the inner face of the fastening member, the part 28, covering the inner faces of the fastening member is then bent, or folded, upon itself, to form the projection 29, is then bent outwardly forming the projection 30 and then inwardly covering the outer face of the fastening member. The plate portion 28 has two cut-outs to allow the passage of the fasteners 21 and 22. A sash cord 31 is attached to the inner face of the metallic element 28, extends upwardly through the recess 24 and carries a weight (not shown) in the frame member 15.

When in position for operation, the plate 20 of the sash is inserted within the recess between the projection 29 and the member 28 of the fastening member and locked in position by the fasteners 21 and 22.

To further prevent longitudinal movement of the sash and fastening member with respect to each other, a pin 32 carried by the metallic fastening member is inserted within a recess 33 in the sash plate 20.

It is to be noted that when the fasteners 21 and 22 are withdrawn, the sash can be removed from the fastening member, whereas, when they are fastened together they will move longitudinally as a unit within the recess of the window frame.

The outer edge of the sash side 10 has a longitudinal recess 34, through which the sash cord 35 passes, the cord 35 being attached to the side 10. The edge 10 has a longitudinal recess 36 and two extended plates 37

and 38. The frame side 14 carries two upwardly extended hooks 39 and 40 capable of insertion beneath the plates 37 and 38 respectively.

5 The operation of the device is as follows:—
The device is in normal position as shown in Figure 1, and the sash and its attached fastening member is capable of vertical movement in the ordinary manner. When it is 10 desired to remove the window, the pin 41 is inserted in the hole 42 of the frame side 15, and the fasteners 21 and 22 are withdrawn, thus freeing the sash from the frame. The sash can then be entirely withdrawn from 15 the frame, and the sash weight will draw the fastening member upward until it contacts with the pin 41. In order to facilitate the washing operation of the outer face of the glass carried by the sash, the hooks 39 and 40 20 are inserted beneath the plates 37 and 38, thus suspending the sash, and as there is only sash weight operating, that is, the one carried by the cord 35, there will be no excessive upward pull upon the sash, and it can be 25 readily manipulated. The dot-and-dash lines in the drawings show the position of the sash in its several withdrawal positions, and similar parts in these drawings are shown in prime numerals.

30 I have shown my device as applied to the lower sash of a window, but it is evident that it is similarly applicable to upper sashes.

It will thus be seen that my invention presents a window in which the sash can be 35 readily removed and replaced and in which the device can be incorporated within the usually employed window frames.

I do not limit myself to the particular size, shape, number or arrangement of parts 40 as these are given simply as a means for clearly describing the device of my invention.

What I claim is:—

45 1. In a window sash, in combination, a window sash frame; an L-shaped cut-out in the outer corner of one side of said sash frame; a metallic plate fixedly attached to the outer edge face of said sash frame and extending beyond said face, forming a recess 50 with the wall of said cut-out portion; a window frame; a slidable fastening member carried by one side of said window frame; a metallic plate fixedly attached to the exposed face of said fastening means, a portion 55 of said fastening member being positioned within said recess and longitudinally removable therefrom; a sash weight carried by said fastening member, and a sash weight carried by the other side of said sash frame, said sash frame being capable of pivotal movement from within said frame.

60 2. In a window sash, in combination, a window sash frame; an L-shaped cut-out in the outer corner of one side of said sash frame; a metallic plate fixedly attached to

the outer edge face of said sash frame and extending beyond said face, forming a recess with the wall of said cut-out portion; a window frame; a slidable fastening member carried by one side of said window frame; a metallic plate fixedly attached to the exposed face of said fastening means, a portion of said fastening member being positioned within said recess and longitudinally removable therefrom; a sash weight carried by said fastening member, a sash weight carried by the other side of said sash frame, said sash frame being capable of pivotal movement from within said frame and means for removably attaching said window sash frame 80 to said fastening member.

Signed at New York city, in the county of New York and State of New York, this 15th day of April, 1930.

ZAN RUCHIN.
